UNITED STATES PATENT OFFICE

GEORGE J. RATHBUN, OF TOLEDO, OHIO

OIL-ELECTRIC ENGINE STRUCTURE

Application filed November 10, 1930. Serial No. 494,546.

This invention relates to oil engines, such for example as are adapted for oil-electric locomotives in which an oil engine drives a generator for furnishing electric current to motors operatively connected to the driving wheels.

An important object is to produce a simple and efficient oil engine having the new and improved features of construction and arrangement hereinafter described particularly adapting it for high speeds and large capacity.

Another object is to produce an oil engine particularly adapted for use in an oil-electric locomotive which utilizes portions of the structure thereof as the frame for the locomotive.

Further objects and advantages of the invention will hereinafter appear, and by way of illustration but not of limitation an embodiment of the invention is shown on the accompanying drawings in which—

Figure 1 is a side elevation of an oil engine-electric locomotive showing the base or bed, engine and generator but without the usual accessories necessary for operation thereof, sufficient disclosure being given to afford an understanding of the embodiment of the invention; Fig. 2 is a transverse section on the line 2—2 of Fig. 1; Fig. 3 is a longitudinal plan view of a portion of the engine base or bed; and Fig. 4 is a transverse section on the line 4—4 of Fig. 3.

The illustrated embodiment of the invention comprises an oil-electric locomotive having the usual trucks 1 provided with wheels 2, certain of which are driven by electric motors 3 suitably mounted on the trucks. The trucks 2 are swiveled to an engine base or bed 4. An important feature of this invention resides in the construction of the base 4 which, in the present instance, is formed from a single casting, although it may be made from two or more castings securely connected together.

The central portion 5 of the base 4 is enlarged and suitably shaped to form the lower portion of the generator housing. This, it will be observed is disposed intermediate the forward and rearward trucks 1, thereby ob-

taining a very desirable balanced arrangement. The upper generator housing section 7 is shown bolted to the base section 5 and the sides thereof are bolted to opposed engine housings 8 and 9. The housings 8 and 9 are 55 securely bolted to the base 4.

Crank shafts 9^a are securely connected to the generator quill or shaft 9^b. An engine unit so constructed may be of large capacity and develop high speeds. The number of 60 cylinders may be varied as desired but an outstanding feature resides in separating the cylinders and interposing the heavy rotating mass therebetween, which serves as a fly wheel. In this instance such heavy rotating 35 mass is the generator. This engine is not only exceptionally well balanced and operates satisfactorily at high speeds but also is more compact than any other adapted for as large capacity. It is emphasized that this arrangement provides an engine which operates as a unit and the importance and other advantages thereof will be apparent to those skilled 70 in this art.

In addition to casting a portion of the generator housing integral with the base 4, the crank case 10 for each of the blocks 8 and 9 is made integral with the base. As shown in Fig. 1 the crank cases 10 incline downwardly 80 toward the generator housing section 5 and thereby not only add reinforcement to the base but also tend to increase the strength and rigidity of the central portion thereof.

Adjacent each end of the base 4 is a centrally disposed longitudinal shock bar or 85 strut 11 which is integral with the end portion 12 at one end and the crank case 10 and side braces 13 at the opposite end. From the side braces or arms 13 extend at an angle reinforcing arms 14 which connect to other 90 bracing arms 15. The arms 13 and 15 are integral with longitudinal side arms 16 and extending parallel to the arms 16 are bracing bars 17 integral respectively with the braces 13 and solid end 12. Each end of the base 4 95 is similarly constructed.

It will be seen from the above description that the oil engine forms the frame of the locomotive and the extensions of the engine base provide space for the usual accessories 100

necessary for operating and controlling the mechanism. It is not essential that the bed be cast in a single piece because the generator housing may be integral with one section of the base and this portion may be bolted or otherwise secured to an adjacent bed portion. Furthermore, it might be desirable to cast the generator housing separately and bolt the other sections of the base to it. In any event, the arrangement, when assembled, provides virtually a one-piece construction.

While the form of mechanism shown and described is admirably adapted to fulfill the objects primarily stated, it is to be understood that it is not intended to confine the invention to the one form of embodiment herein disclosed, for it is susceptible of embodiment in various forms all coming within the scope of the claims which follow.

What I claim as new and desire to secure by Letters Patent is:

1. An internal combustion engine having cylinders, pistons and crank shafts, certain cylinders being spaced laterally from the remainder with the crank shafts thereof in alignment, separate housings for said laterally spaced cylinders, a relatively heavy rotatable mass interposed between the laterally spaced, crank shafts providing a fly wheel therefor, a housing for said mass, means for rigidly securing said mass housing directly to said laterally spaced cylinder housings, and connections between said crank shafts and the axis of said rotatable mass.

2. An internal combustion engine unit having cylinders, pistons and crank shafts, certain cylinders being spaced laterally from the remainder with the respective crank shafts in alignment, housings for said laterally spaced cylinders, a rotatable generator interposed between the laterally spaced crank shafts providing a fly wheel therefor, connections between said crank shafts and the axis of said generator, a housing for said generator, a base for said cylinders, and connections between said base, generator housing and cylinder housings providing a rigid structure.

3. In a locomotive, an internal combustion engine having cylinders, pistons and crank shafts, certain cylinders being spaced laterally from the remainder with the respective crank shafts in alignment, housings for said laterally spaced cylinders, a generator interposed between said crank shafts, connections between said crank shafts and the axis of said generator, a rigid base for said cylinder housings, said base and housings also providing the frame for the locomotive, trucks connected respectively to such frame in front and in rear of said generator, and extensions on said base providing a platform for accessories.

4. In a locomotive, an internal combustion engine unit having cylinders, pistons and

crank shafts with the latter in alignment and certain cylinders spaced laterally from the remainder, housings for said laterally spaced cylinders, a generator interposed between said crank shafts, a rigid base for said cylinder housings, a generator housing, connections between said base, generator housing and cylinder housings providing a rigid structure, and trucks connected respectively to said base in front of and in rear of said generator.

5. In a locomotive, laterally spaced trucks, an internal combustion engine having its base mounted directly on said trucks and providing the frame for the locomotive, said engine comprising cylinders, pistons, and a pair of crank shafts, certain of said cylinders being spaced laterally from the remainder and said shafts being arranged in alignment, housings for said laterally spaced cylinders, a generator disposed centrally of said base and between said crank shafts, connections between said crank shafts and the axis of said generator, and a housing for said generator rigid with said base and said cylinder housings.

In testimony whereof I have hereunto signed my name to this specification.

GEORGE J. RATHBUN.
